United States Patent Office

Des. 193,218
Patented July 10, 1962

193,218

BOTTLE OR SIMILAR ARTICLE

Victor Koenigsberg, 702 Hall St., Franklin Square, N.Y.

Filed Jan. 30, 1962, Ser. No. 68,572

Term of patent 14 years

(Cl. D58—6)

Fig. 1

Fig. 2

Fig. 3

FIG. 1 is a front elevational view of a bottle or similar article embodying my new design;

FIG. 2 is a side elevational view of said bottle; and

FIG. 3 is a top plan view thereof.

The back and side not shown are the same respectively, as the front and side shown.

I claim:

The ornamental design for a bottle or similar article, as shown and described.
